Primary Examiner — Holly Baynam*Assistant Examiner* — Rhea Shields*(74) Attorney, Agent, or Firm* — Marger Johnson(57) **CLAIM**

The ornamental design for a two-in-one brush, as shown and described.

DESCRIPTION

FIG. 1 is a first perspective view for a two-in-one brush;

FIG. 2 is a second perspective view thereof;

FIG. 3 is a third perspective view thereof;

FIG. 4 is a front view thereof;

FIG. 5 is a rear view thereof;

FIG. 6 is a top view thereof;

FIG. 7 is a bottom view thereof;

FIG. 8 is a left view thereof; and,

FIG. 9 is a right view thereof.

In the drawings, the broken lines are for the purpose of illustrating environment only and form no part of the claimed design.
